UNITED STATES PATENT OFFICE.

GEORGE B. KING, OF LAWRENCE, MASSACHUSETTS, ASSIGNOR OF ONE-HALF HIS RIGHT TO WILLIAM J. DORRINGTON, OF SAME PLACE.

IMPROVEMENT IN STREET-SIGNS.

Specification forming part of Letters Patent No. **159,550**, dated February 9, 1875; application filed January 18, 1875.

To all whom it may concern:

Be it known that I, GEORGE B. KING, of Lawrence, in the county of Essex, State of Massachusetts, have invented a certain new and useful Improvement in Street Signs, of which the following is a description sufficiently full, clear, and exact to enable any person skilled in the art or science to which my invention appertains to make and use the same, reference being had to the accompanying drawing, forming a part of this specification, in which—

Figure 1 is a plan, and Fig. 2 an isometrical perspective view.

Like letters of reference indicate corresponding parts in the different figures of the drawing.

My invention relates more especially to that class of street-signs which are designed to be attached to or supported by lamp-posts; and consists in a novel construction and arrangement of the parts, as hereinafter more fully set forth and claimed, by which a simpler, cheaper, and more effective device of this description is produced than is now in ordinary use.

The extreme simplicity of my invention renders an elaborate description unnecessary.

In the drawing, A represents a section of an ordinary lamp-post, provided with the rungs or hafts *b b*. A clamp-collet, C, formed in two parts, is united around the post by the nuts and bolts D D. Projecting from the collet are two arms, E E, to which are attached the sign-boards F G by the screws *a c*. These signs are composed of thin sheet metal, properly painted, and are designed to be lettered to indicate the streets to which they refer, being provided at their outer ends with the index-fingers or pointers *m m*.

It will be obvious that the collet C may be readily fitted to lamp-posts already erected, in such a manner that its signs will correspond with the direction of the streets, and also that any number of signs desired may be supported in this manner.

Having thus explained my invention, what I claim is—

The signs F G, having the indexes *m m*, and provided with the clamp-collet C, substantially as and for the purpose specified.

GEORGE B. KING. [L. S.]
